UNITED STATES PATENT OFFICE.

LOUIS STEINBERGER, OF BROOKLYN, NEW YORK.

INSULATOR.

1,403,717.

Specification of Letters Patent. Patented Jan. 17, 1922.

Application filed January 17, 1918. Serial No. 212,337.

To all whom it may concern:

Be it known that I, LOUIS STEINBERGER, a citizen of the United States, and a resident of the borough of Brooklyn, county of 5 Kings, State of New York, have invented certain new and useful Improvements in Insulators, of which the following is a specification.

My invention relates to insulators for use 10 either as strain insulators or as suspension insulators, in which the strain members are provided with compression surfaces or discs, the said compression surfaces or discs being situated opposite to each other and embedded in the insulating material.

One of the objects of my invention is to provide opposing discs for the compression surfaces of the respective strain members for the purpose of disposing more of the 20 insulating material between those faces than could possibly be disposed between the strain members of ordinary construction.

Another object is to provide an insulator with improved strain members which will 25 stand up more effectually under greater mechanical stress than will an insulator which is provided with strain members of ordinary structure, and which improved strain members will at the same time act as distributing 30 elements for the electrical stresses, and thus tend to prolong the life of the insulator.

Other objects will appear from the following specification and claims.

Referring to the drawings in which similar reference characters refer to like parts in the various figures;

Fig. 1 is a view partly in section and partly in side elevation of an insulator embodying my invention.

40 Fig. 2 is a side elevation of the insulator shown in Fig. 1, viewed at a point 90° therefrom.

Fig. 3 is a section on line 3—3 of Fig. 1.

Fig. 3^a is a section on line 3^a—3^a of Fig. 1.

45 Fig. 4 is a view partly in elevation and partly in section of a modified form of my invention.

Fig. 5 is a view in elevation of one of the strain members used in the construction 50 shown in Fig. 4.

Fig. 6 is a section on line 6—6 of Fig. 4.

Fig. 7 is a detail view in vertical section.

Figs. 8, 9 and 10 are details in horizontal cross section of the disc supporting shanks.

55 Referring to the drawings, it is to be noted that the construction shown in Figs.

1 and 2 is distinguished primarily from that shown in Fig. 4 in the particular form of strain member used, the strain member of the construction shown in Fig. 4 being approximately one half of the strain member shown in Fig. 1, and provided with an open hooked portion by means of which it can be readily coupled to and uncoupled from the strain member of the adjacent insulator. 60

The insulating material may be of any suitable kind but I prefer to use the insulating material known in the art as "electrose," and the other parts are formed of any suitable metal or alloys thereof. 70

Referring to Figs. 1, 2, 3 and 3^a, the strain members 10 and 11 are interlocked one with the other as shown, and portions of each are embedded in an insulating body E, the strain member 10 being formed of an integral piece 75 of metal and the strain member 11 being formed of two U shaped portions 12 and 13, the free ends 14 of each being screw threaded at 15 and secured to each other by nuts 16 and 16' engaging with the screw threads, 80 as clearly shown in Fig. 1.

The respective strain members are provided with circular plates or discs 20 and 21 having shanks 22 and 23 extending from one side thereof, the said shanks being constructed to be secured to the bridge portions 24 of the strain members. To this end the disc 20 is provided with a shank 22 having screw threads at the outer end thereof which engage with a screw threaded cavity 26 in 90 the bridge 27 of the integral strain member, and the disc 21 is provided with a shank 25 which fits into a cavity 28 in the bridge portion of one of the parts constituting the strain member 11. 95

The shank 25 of the disc 21 is provided with a tenon 29 extending therefrom, screw threaded at its outer end at 29' for engagement with a securing nut 29'' as shown. The shank portion 25 is keyed to the bridge 100 member as shown at 31 to prevent it turning around and thus causing short circuiting between the strain members.

Many other suitable well known means may be provided for preventing the turning 105 of the strain member on the shank of the disc.

In the embodiment of the invention shown in Figs. 4 to 6, the oppositely disposed circular plates or discs 40 and 41 are secured to 110 the horizontally projecting arms 42 of the strain members 10' and 11', each plate being

secured to its respective arm in the same way, so that the parts constituting the strain members and the discs are duplicates of each other. This duplication of parts assists materially in the saving of cost in manufacture.

The strain members 10' and 11' consist of a rod having a horizontal projecting portion 42 at one end and a hook portion 45 at 10 the other end, the hook portion 45 being constructed to securely hook into the adjacent hook of another strain member, thereby connecting one insulator with its adjoining insulator. The construction is also such 15 that the parts may be readily disconnected. The shanks 22' are constructed with a projecting tenon 46 provided at the ends with screw threads 47 for engagement with nuts 48 and washers 49 as clearly shown in the 20 drawings, so that the tenons may pass through holes 50 made for that purpose in the horizontally projecting portions of the strain members, and be secured thereto by the nuts and washers.

25 Suitable keys 51 are used as shown to prevent the discs from turning around on their axes, and thus prevent short circuiting between the strain members.

Another means which is available for 30 securing the discs to the horizontal portion of the strain member and from preventing the discs from turning on the axes of their shanks is shown in Fig. 7. As there shown, the shank 60 is provided with a tenon 61 35 having screw threads 62 on its outer surface engaging with the screw threaded hole 63 in the horizontal portion 64 of the strain member 11'. A small screw 65 is secured in place as shown in the screw hole 66 provided for that purpose at the junction of the 40 two screw threaded surfaces.

These shanks to which the discs or circular plates are secured may be made square in horizontal cross section, or any other 45 shape not round, or they may be made round with a projecting ridge 70, or with a depression 71 for anchoring in the insulating material, to prevent turning, as indicated in the horizontal cross-sectional views Figs. 8, 9 50 and 10, which constructions when used dispense with the use of keys.

Extending from the shank portions hereinabove described, are integral flanges 75, 76, 75', 76', which abut the respective ends 55 of the insulating bodies, thereby protecting the insulating bodies from the bridge portions of the strain members and rendering the insulating bodies less likely to become broken or chipped in use.

60 As will be seen, the discs and plates form compression surfaces for the strain members and they are of such area that when they are embedded in the insulator E a large body 65 of insulating material is situated between the surfaces of the discs or plates. By this con-

struction, the insulator will resist great electrical and mechanical stress and the electrical stresses will be distributed to a large degree. The disc or plate construction will dispose the electro static stress over a comparatively large area of insulating material and thereby reduce its concentration and thus increase the life and value of any given insulator for certain voltages.

As changes of construction could be made 75 within the scope of my invention, it is intended that all matter contained in the above description shall be interpreted as illustrative and not in a limiting sense.

Having now described my invention, what 80 I claim as new and desire to secure by Letters Patent is:

1. In a device of the kind described, interlocking strain members in combination with a body of insulating material having molded therein oppositely disposed discs of metal, a shank extending respectively from each disc and projecting beyond the body of insulating material, means on each shank to detachably and removably secure the same 90 to its respective strain member.

2. In a device of the kind described, interlocking strain members, a body of insulating material, oppositely disposed electrical stress distributing discs molded therein, a 95 single shank connected to each of the respective discs and extending outwardly from the insulating body, separate means for detachably and removably securing each shank to its respective strain member, and means for preventing a strain member from turning.

3. In a device of the kind described, a body of insulating material, interlocking strain members, oppositely disposed metallic discs in said body, each disc being provided with means for detachably and removably securing the same to its respective strain member.

4. In a device of the kind described, a body of insulating material, interlocking strain members, oppositely disposed compression discs molded in said insulating body, a single shank projecting from each disc and extending outside of the body of insulating material, means on each shank 110 connecting with means on each strain member for detachably and removably securing each shank to its corresponding strain member.

5. In a device of the kind described, interlocking strain members, a body of insulating material having oppositely disposed electrical stress distributing elements and having portions thereof projecting axially from the insulating body, separate means for securing each electrical stress distributing member to its respective strain member.

6. In a device of the kind described, interlocking strain members, a body of insulating material, oppositely disposed stress dis- 130

tributing discs molded therein, a shank connected to each disc, a portion of each of which extends outwardly from the body of insulating material, means for detachably and removably securing each shank to its strain member, and means for preventing each strain member from turning.

5 In witness whereof, I have hereunto set

my hand at the borough of Manhattan, city and State of New York, this fifteenth day 10 of January, 1918.

LOUIS STEINBERGER.

In presence of—
C. C. BILLINGS,
ZITA M. GRAHAM.
